UNITED STATES PATENT OFFICE.

GEORGE M. LANE, OF ASBURY PARK, NEW JERSEY.

ELECTRIC-ARC LIGHT.

SPECIFICATION forming part of Letters Patent No. 350,140, dated October 5, 1886.

Application filed March 31, 1886. Serial No. 197,339. (No model.)

To all whom it may concern:

Be it known that J. GEORGE M. LANE, a citizen of the United States, residing at Asbury Park, in the county of Monmouth and State 5 of New Jersey, have invented certain new and useful Improvements in Electric-Arc Lamps; and I do declare the following to be a full, clear, and exact description of the invention, such as will enable others skilled in the art to 10 to which it appertains to make and use the same, reference being had to the accompanying drawings, and to the letters and figures of reference marked thereon, which form a part of this specification.

15 My invention relates to arc lamps of that class in which either curved or arc-shaped points or straight points are employed; and it has for its object to provide a simple, cheap, and positive means for holding such points and 20 feeding them in such manner that the voltaic arc shall maintain a nearly fixed position relative to the parts of the lamp, a further object being to reduce the lamp to a compact form, and yet maintain the greatest possible length 25 of points.

It consists in the novel features more fully hereinafter set forth, claimed, and shown in the annexed drawings, in which—

Figure 1 is a side view of a lamp of my construction complete and ready for use. Fig. 2 is a similar view on an enlarged scale with the casing and globe removed. Fig. 3 is an end view; Fig. 4, an enlarged detail view of the pawl and the feeding-wheel. Fig. 5 is a detail view of the means for disconnecting the segments when adjusting the carbons, and Fig. 35 6 is a modification.

The case A² may be of any suitable shape commonly used in this class of articles, and 40 incloses the operating parts of the lamp. Hood or shield B², depending from the under side of the casing, may be used as a reflector, and at the same time serve as a support for the globe C. By supporting the globe from above and 45 having all the operating parts as well as the carbon-holders located above the arc, all possibility for the casting of deep shadows, as is usual with lamps of ordinary construction, is entirely obviated.

50 Within case A² is located the electro-magnets D D', the latter being of a high resist-

ance compared with the former. These magnets are arranged at opposite sides of the case, and between them is pivoted a lever, E, provided with armatures e e' at each end, respectively. Bracket F, depending from the lever E, has adjustably connected therewith a pawl, G, which works through a guide in the bottom of the case, for a purpose presently made apparent. Supports H H', depending from the case 55 to A, are provided with short shafts or arms h h' near their lower ends, respectively, which are in axial line and terminate at a short distance from each other. Mutilated or segment gears I I' are journaled on said shafts or arms, respectively, and are provided with carbon-holders i i', respectively. These holders may project from the plane of the segments toward each other, so as to be nearly in the same plane to permit the entire consumption, or nearly so, 60 of the points; but for practical purposes the holders may be in the same plane with the respective segments, which are arranged in close relationship to each other. Pinions J J' are mounted on shafts j j', journaled between the 65 upper ends of the supports or brackets H H'. The shafts are at unequal distances from the axis of the segments, thus permitting the pinions to be of unequal sizes, so that the points I² I³ may be fed at different rates of speed to 70 compensate for the greater consumption of the positive point and maintain a fixed position of the arc. The pinion J meshes with a pinion, J², on the shaft j', and imparts motion thereto. On said shaft j' is likewise mounted 75 a toothed disk or gear-wheel, J³, which is engaged and has its movements controlled by the pawl G. The shafts j j' will be suitably insulated from the supports, and in each case the insulation will be at one end only, and to 80 prevent short-circuiting the lamp the pinion J² will be insulated from its shaft.

In practice the current from the line-wire enters at L, thence through support H', shaft h', segment I', points I² I³, segment I, shaft h, support H, leaving at I', where it again joins the line. The current in its passage likewise passes through the magnets D D', which are included in the circuit, and vibrates the lever E in the usual manner. When the current first 85 passes, the magnet D is energized, which, attracting the armature e, elevates the opposite 90 95 100

one, e' , which carries with it the pawl G. The latter, engaging a tooth of disk J, rotates the segments in opposite directions, as indicated by the arrow. This separates the points and 5 establishes the arc in a manner well understood. As the resistance increases, the energy of magnet D' predominates, whence it attracts the armature e' , effecting a disengagement of the pawl from the disk J³. The points, being 10 freed, gravitate toward one another till held in check by the predominant energy of magnet D. In case the lamp should become inoperative and the points refuse to feed, and in order that the system may not be impaired thereby, a 15 shunt, M, located in the case A, affords a passage for the current through the lever E and contacts m m' to the line, thus cutting the lamp out of circuit. To prevent the too great feed of the points at the moment the pawl G is dis- 20 engaged from the disk J³, a supplementary pawl, g, is provided and pivoted to the pawl G to engage a tooth of said disk. The shaft j is so arranged that the pinion J may be thrown out of engagement, so that either carbon-holder may be moved without disturbing 25 the other, when desired, as shown in Fig. 5. The segment-levers I I' have projections A A' on the sides farthest from the carbon-holders. These projections are arranged to engage pins 30 B B' on the supports H H', forming a short circuit, so that the lamp will be automatically cut out before the carbons are entirely consumed, thus saving the carbon-holders from being destroyed.

35 Having thus described my invention, what I claim, and desire to secure by Letters Patent, is—

1. In an arc lamp, the combination, with the segments having the carbon-holders, of the driving-pinions and means, substantially as 40 set forth, for throwing one of said pinions into and out of gear with the corresponding segment, substantially as set forth, whereby one carbon may be adjusted independently of the other. 45

2. In an arc lamp, the combination of the segments, the supports provided with pins forming terminals provided with holders, and having corresponding projections to engage with the pins and short-circuit the lamp, the 50 differential gearing meshing with said segments and moving them at different rates, the reciprocating pawl for actuating said gearing, and a supplementary pawl carried by said reciprocating pawl to limit and hold in check 55 the movement of said gearing, substantially as and for the purpose set forth.

3. In an arc lamp, the combination of the supports H H', provided with projections B B', shafts h h' in axial line, segments I I', provided with holders i i' and projections A A', shafts j j' at different distances from the peripheries of the segments, differential gearing J J' J², toothed disk J³, keyed to one of said shafts, and the reciprocating pawl G, provided 60 with the supplementary pawl g, substantially as and for the purposes set forth.

In testimony whereof I affix my signature in presence of two witnesses.

GEORGE M. LANE.
